UNITED STATES PATENT OFFICE

CLARA BORCHMANN, OF NEW YORK, N. Y.

COVER FOR RECEPTACLES.

1,210,892.

Specification of Letters Patent. Patented Jan. 2, 1917.

Application filed December 3, 1915. Serial No. 64,835.

To all whom it may concern.

Be it known that I, CLARA BORCHMANN, a subject of the Emperor of Germany, residing at New York, in the county of Bronx and State of New York, have invented new and useful Improvements in Covers for Receptacles, of which the following is a specification.

This invention relates to covers for receptacles and has particular application to covers for bottles.

In the present instance it is my purpose to provide a cover which will completely envelop and conceal the bottle in such a manner that the outline and form of the bottle will be completely obliterated and no suspicion whatever will be aroused as to the presence of such bottle.

It is also my purpose to provide a cover which when applied to the bottle will not interfere with the pouring of the contents from the latter. Furthermore, I propose to provide a bottle concealing cover which may be adapted to the bottle in such manner that it will not become accidentally disengaged from the bottle under the ordinary handling to which the latter may be subjected.

With the above recited objects and others of a similar nature in view, my invention consists in the construction, combination and arrangement of parts set forth in and falling within the scope of the appended claims.

In the accompanying drawings:—Figure 1 is a front view of my invention as employed in concealing the bottle. Fig. 2 is a vertical sectional view taken through the bottle and the figure or covering therefor, and showing a movable part, such as the head of the figure in position to permit of pouring from the bottle. Fig. 3 is a sectional view taken on the irregular line 3—3 of Fig. 2.

In carrying out my invention I prefer to provide a cover in the nature of a figure which is an imitation or simulation of a living creature, and in the present instance this covering figure represents a human being dressed with a garment which assists in effecting the concealment of the receptacle or bottle.

Referring now to the accompanying drawings in detail, the numeral 5 represents a bottle which may be of the usual form, having a neck 6 extending up from the usual shoulder 7, said neck being provided with a

removable stopper 8, and below which the neck is formed with an ordinary circumferential rib or bead 9. The bottle is normally completely enveloped and concealed by means of a covering figure 10, said figure being preferably in the form of a girl doll having a stuffed body or trunk section 11. This trunk section is preferably made by stitching together or otherwise uniting the meeting edges of the outer fabric section 12 and the inner fabric section 13, the latter being preferably doubled upon itself to form a two ply section, the latter constituting an inner approximately cylindrical wall which is adapted to surround the bottle neck. It will be understood that the two united sections of fabric form a bag like member which may be stuffed with a soft filling of any suitable material, such as cotton, cloth or sawdust, as indicated by 12a. This trunk section is further reinforced or stiffened by means of a frame comprising an upper or neck ring 12b and a lower or waist ring 12c, and vertical side rods 12d. Preferably, the two rings and the vertical stiffening rods are located between the two folds of the inner wall section 13 as shown in Fig. 2. This stiffening frame is preferably made of wire and not only reinforces and maintains the shape of the trunk section, but also assists in holding the latter on the bottle, for as the inner wall section forms a tubular sleeve or vertical opening through the trunk section to receive the neck of the bottle, the upper wire ring 12b being slightly resilient, will clamp against the upper end of the neck adjacent the mouth of the bottle, while the lower or waist ring 12c will likewise clamp against the base portion of the neck adjacent the top of the bottle. This trunk or bust portion of the covering figure is preferably completely covered by a garment 14 which may be of fabric, paper or other suitable material, this garment 14 being in the nature of a blouse which is provided with a nether section or skirt 15 which drops or falls to the bottom of the bottle, or in position to substantially touch a horizontal support on which the bottle may rest. If desired, this garment may be made in one piece.

The covering figure is preferably made ornamental in appearance, and may be provided with a suitable fancy apron 16, and is also preferably provided with a relatively wide collar 17 of cloth or similar material,

for the purpose hereinafter mentioned. The head 18 is preferably formed of porcelain or similar rigid material and may be movably attached to the trunk section of the figure by a simple hinged connection 19 which, if desired, may be in the form of stitches, connecting either the rear or front lower edge of the head portion to the upper portion of the trunk. By thus attaching the head, the latter may normally occupy the position indicated in Fig. 1, thus concealing the mouth end of the bottle, but, when desired, said head may be swung back to the position illustrated in Fig. 2, so that the stopper of the bottle will be exposed. When this stopper is removed, the contents of the bottle may be poured out as usual.

For the purpose of further insuring that the covering figure will not become accidentally detached or removed from the bottle, I may, if desired, provide a circumferential band 20 of elastic material such as is commonly employed for making garters. This band is preferably attached to the inner 25 ply of the material of the wall 13, as shown in Fig. 2, and may be readily stretched or opened out so as to permit it to be passed over the neck of the bottle and down to a point below the rib or bead 9. The waist-line 22 of the figure is preferably located at the base of the neck 6 of the bottle so that the shoulder 7 of the bottle gives shape to the hip sections 23 of the figure.

It will be evident that while the covering figure completely covers the true identity of the article, the bottle will operate as a support for the figure and assist in giving shape to the latter. In this connection it is to be understood that the skirt 15 of the figure is 30 preferably made from flimsy cloth, paper or the like.

The collar 17 projects downwardly beyond the lower edge of the head portion of the figure so that it effectively conceals the fact 45 that the head is movable, as such collar overlies a separation of the neck at the shoulders of the figure. At the back the lower edge of the collar may be attached by sewing it to the back of the trunk below the hinged connection 19.

While I have herein described my bottle cover as having a movable head or part to give access to the stopper, I may if desired, remove the cover bodily from the bottle 55 when the latter is to be used.

While I have herein shown and described one particular embodiment of my invention, I wish it to be understood that I do not confine myself to all the precise details of construction herein set forth by way of illustration, as modification and variation may be made without departing from the spirit

of the invention or exceeding the scope of the appended claims.

What I claim is:—

1. A bottle cover comprising a body portion shaped to approximately the contour of the trunk of the human body and having a walled opening longitudinally therethrough adapted to receive and conceal the neck of a bottle, a head section mounted on the body portion and adapted to overlie the mouth of a bottle and a nether section depending from the body portion and adapted to cover and conceal the body of a bottle.

2. A bottle cover comprising a body section having an elongated walled opening extending longitudinally therethrough for the insertion of a bottle neck, said body section conforming in outline to the general shape of the trunk of a human body, a head section movably connected with the body section and adapted to be positioned to conceal and expose the mouth of a bottle, and a nether section depending from the body section and covering the body of the bottle.

3. In a device of the character set forth, in combination, a bottle having a neck and a removable stopper therefor, a figure of a doll having a body with an opening therethrough receiving the said neck of the bottle, said opening having means therein for engaging the neck of the bottle to secure said body thereto, and a skirt of flexible material extending down from said body and coöperating with said body to envelop and completely conceal said bottle, said doll having a movable head attached thereto movable into a position to expose said stopper.

4. In a device of the character set forth, in combination, a bottle having a neck and a removable stopper therefor, a figure of a doll having a body with an opening therethrough receiving the said neck of the bottle, said opening having means therein for engaging the neck of the bottle to secure said body thereto, and a skirt of flexible material extending down from said body and coöperating with said body to envelop and completely conceal said bottle, said doll having a movable head attached thereto movable into a position to expose said stopper, said figure having its waist line substantially at the base of said neck, said bottle operating to support said figure in an upright position, the shoulder of the said bottle giving shape to the hips of the said figure.

In testimony whereof I have hereunto set my hand in presence of two subscribing witnesses.

CLARA BORCHMANN.
